AKTIENGESELLSCHAFT, OF ESSEN-ON-THE-RUHR, GERMANY.

STORING APPARATUS FOR EXHAUST-STEAM HEAT.

1,128,372.

Specification of Letters Patent.

Patented Feb. 16, 1915.

Application filed May 27, 1913. Serial No. 770,174.

To all whom it may concern:

Be it known that I, CURT SCHRAEPLER, residing at Essen-on-the-Ruhr, Germany, a subject of the Emperor of Germany, have 5 invented a certain new and useful Improvement in Storing Apparatus for Exhaust- Steam Heat, of which the following is a specification.

This invention relates to storing apparatus for exhaust steam heat with floating bell, and its object is to provide a heat storing apparatus of this kind of simple construction, having large cooling- and reëvaporating-surfaces, wherein the fluid, which serves 15 as heat absorber, is automatically circulated by the steam pressure, making a special pump unnecessary.

Two embodiments of the present invention are illustrated in the accompanying 20 drawings, wherein—

Figure 1 shows one of the embodiments in a vertical section along the longitudinal axis, and Fig. 2 a similar view of the second embodiment of the invention.

25 Referring first to Fig. 1, which represents a heat storing apparatus constructed as a gas-meter, this device consists principally of a stationary tank A partly filled with water B, which serves as heat absorber, and a floating bell C guided in the tank A. An oil-seal D covers the part of the water bath B which is situated between the inner cylindrical surface of the tank A and the outer cylindrical surface of the floating bell C. 30 A branch pipe e¹ leads from the main E of the exhaust steam into the tank A. This branch pipe opens into a tube F, suspended from the dome of the bell C, and is guided by a sleeve f¹ secured at the lower end of 35 the tube. At the upper end of this tube F, are provided several openings f², for the passage of the exhaust steam. A number of tray-shaped vessels G, of slightly smaller diameter than the bell, are placed one above 40 the other and built into the bell C in such a manner that all of them will be covered by the water bath B, when the bell is in its lowest position; but that all of them will be above the surface of the water, when the 45 bell stands in its highest position, abutting against the stops a¹ of the tank A. Still another pipe H, opening into the atmosphere, is provided in the bell C, and this pipe is given such a length, that its lower 50 opening stands just above the surface of 55 the water, when the bell C is in its uppermost position; but with the bell lowered, the pipe is passed into the water. If there is a greater quantity of exhaust steam than can be consumed, the surplus of the exhaust 60 steam passes through the pipe e¹, tube F and openings f² into the interior of the floating bell C. Supposing the latter to be situated in its upper middle position, only the lower vessels G then stand below the surface of the 65 water B, while the upper ones are filled with water and stand above said surface. In consequence of the contact of the exhaust steam with the cool upper surface of the upper vessels G, and with the water bath B, as well 70 as with the walls of the bell C, a portion of the exhaust steam will be condensed. Any still remaining surplus of exhaust steam will then cause the bell C to rise, whereupon also the lower vessels G, one after the other, will 75 rise and offer additional contact surfaces to the exhaust steam. In consequence of the enlargement of the contact surfaces, the amount of condensation will naturally be 80 greater, so that generally an equilibrium 85 soon will be reached, whereby the amount of condensed exhaust steam will be the same as the amount supplied and consequently the bell does not rise farther. Under the supposition, that the exhaust steam supply is so 90 great, that not all of the exhaust steam can be condensed, when all of the vessels G have been raised from the water bath B, the bell C will then rise until it strikes against the 95 abutments or stops a¹. In this position, the 100 lower opening of the pipe H will be situated above the surface of the water, so that the surplus steam may escape through the pipe H into the atmosphere. Should more exhaust steam have to be consumed than what 105 the exhaust steam main E is capable of supplying, additional steam will be drawn for the heat storing apparatus. Supposing now that the floating bell, to start with, is situated in its middle position. In consequence 110 of the escape of the steam from the storing apparatus, the pressure under the bell C will diminish, and as a consequence a reëvaporation, increasing the amount of steam will take place, which evaporation is greatly 115 favored by the large water surfaces of the vessels G situated above the water bath B. The bell C will simultaneously sink in consequence of the diminishing pressure in the bell C. The vessels G will then one after 120

the other be passed into the water bath B, and the water contained in the vessels, which has been warmed by the previous absorption of condensed steam, now mixes with the 5 cooler water in the tank A, whereupon the vessels, upon the subsequent rising of the bell C, will again contain cooler water.

The second embodiment of the present invention, see Fig. 2, distinguishes over the 10 one first described simply thereby, that the vessels G have been replaced by a sprinkling device, which is constructed in the following manner: A number of annular vessels J and K are arranged alternately above each 15 other in the bell C. The vessels J, which are provided with holes ν^1 in the side and bottom, are seated on similarly perforated disks M, which in their turn lie on rods N, secured in the bell C. The vessels K are 20 suspended from rods P, which are also secured in the bell C. Several pipes Q, distributed over the whole bottom surface, reach out from the bottom of the vessels K, and which are divided into two branches q^1 25 and q^2 . One of these pipe-branches q^1 opens above a perforated annular plate R, secured to the tube F; and the other branch q^2 opens above another perforated annular plate T, situated on a level with plate R, and secured 30 on the cylindrical surface of the bell C. The manner of operation is substantially the same as in the first described embodiment. The water lifted by the vessels J and K, on the rising of the bell C, does, however, not 35 remain therein, but flows instead gradually off through the holes ν^1 furnished in the vessel J and through the pipes Q, attached to the vessels K. In consequence of the perforations in the plates M, R and T, 40 the flowing off water will be very finely distributed, whereby the exhaust steam, entering the bell C, will be condensed to a much higher degree, than what is the case in the first described embodiment of the invention. 45 An advantage common to both of these embodiments is, however, that the vessels, built into the bell C, resist any sudden rising of the bell and therefore provide a powerful brake for the bell against any 50 shocks from the steam.

I claim:

1. In a storing apparatus for exhaust steam heat, having a fluid tank and a bell floating therein; means for supplying steam 55 to said bell, and means for steam escape therefrom; a plurality of vessels within the bell and capable of rising and falling therewith, whereby fluid will be scooped up and raised by said vessels on the rising of the bell.

2. In a storing apparatus for exhaust steam heat, having a fluid tank and a bell floating therein; means for supplying steam to said bell; said means comprising a tube 60 suspended from the dome of said bell with

side openings at its upper end, and a pipe connected with a steam supply opening into said tube and telescoping therewith on the reciprocation of the bell; means for steam escape from said bell; a plurality of vessels 70 situated at different levels within the bell and capable of rising and falling therewith, whereby fluid will be scooped up and raised by said vessels on the rising of the bell.

3. In a storing apparatus for exhaust steam heat, having a fluid tank and a bell floating therein; means for supplying steam to said bell; said means comprising a tube suspended from the dome of said bell with side openings at its upper end, and a pipe 75 connected with a steam supply opening into said tube and telescoping therewith on the reciprocation of the bell; means for steam escape from said bell, said latter means comprising a pipe suspended from the dome, 80 opening into the atmosphere and having an opening at its lower end slightly above the lower rim of said bell; a plurality of vessels situated at different levels within the bell and capable of rising and falling therewith, 85 whereby fluid will be scooped up and raised by said vessels on the rising of the bell.

4. In a storing apparatus for exhaust steam heat, having a fluid tank and a bell floating therein; means for supplying steam 90 to said bell; said means comprising a tube suspended from the dome of said bell with side openings at its upper end, and a pipe connected with a steam supply opening into 95 said tube and telescoping therewith on the reciprocation of the bell; means for steam escape from said bell; a plurality of vessels situated at different levels within the bell and capable of rising and falling therewith, 100 whereby fluid will be scooped up and raised by said vessels on the rising of the bell; said vessels being provided with perforations for permitting the scooped up fluid to gradually 105 flow off therefrom.

5. In a storing apparatus for exhaust 110 steam heat, having a fluid tank and a bell floating therein; means for supplying steam to said bell, and means for steam escape therefrom; a plurality of vessels situated at different levels within the bell, said vessels having perforated sides and bottom, and being capable of rising and falling with said bell, whereby the fluid will be scooped up and raised by said vessels on the rising of 115 said bell and sprinkled through said perforations of the vessels.

6. In a storing apparatus for exhaust steam heat having a fluid tank and a bell floating therein; means for supplying steam to said bell and means for steam escape 120 therefrom, a plurality of vessels with perforated sides and bottom suspended at different levels in said bell, and other similarly suspended vessels alternating with the first named vessels at different levels, said 125 130

second vessels having solid sides and bottom, 5
annular plates suspended in said bell level
with the bottom of said second vessels, said
annular plates being provided with perfora-
tions, and pipes connecting the interior of
said second vessels with the upper side of
said annular plates; whereby fluid will be
scooped up and raised by said vessels on the

rising of said bell and sprinkled through
said perforations of the vessels and plates. 10

The foregoing specification signed at Bar-
men, Germany, this 10th day of May, 1913.
